[57] CLAIM

The ornamental design for a semi-truck trailer, as
shown and described.

DESCRIPTION

FIG. 1 is a top plan view of the novel semi-truck trailer;
FIG. 2 is a side elevational view thereof the opposite
side being a mirror image of that shown;
FIG. 3 is a bottom plan view thereof;
FIG. 4 is a frontal elevational view thereof;
FIG. 5 is a rear elevational view thereof; and,
FIG. 6 is a perspective view of the novel semi-truck
trailer on a greatly reduced scale, it being understood
that the broken lines are for illustrative purposes only
and form no part of the claimed design.
